(57) **CLAIM**

The ornamental design for an outdoor landscape lamp, as shown and described.

DESCRIPTION

FIG. 1 is a perspective view of an outdoor landscape lamp, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines illustrate portions of the outdoor landscape lamp that form no part of the claimed design. Areas illustrated in stippling indicate a contrast in appearance.
